ELECTRIC SIGN

Frank I. Braun, Orange, N. J., assignor to General
Electric Vapor Lamp Co., Hoboken, N. J., a cor-
poration of New Jersey

Application August 17, 1928, Serial No. 300,159

8 Claims. (Cl. 40—130)

Special objects of this invention are to provide a sign or display of the neon or argon gas type, which can be changed or made up to spell different words or form different figures or designs 5 and in which the various interchangeable units of the device may be formed all alike and be made up, as required to form any desired luminous letter or figure.

These objects are attained by certain novel features of construction, combination and relations of parts as hereinafter described and claimed.

In the drawing forming part of the present specification, several different possible embodiments of the invention are illustrated, but it 15 should be understood that the structure may be modified as regards these particular disclosures without departure from the true spirit and broad scope of the invention.

Fig. 1 is a broken front view of a four unit electric sign embodying the invention; Fig. 2 is a detached perspective view of one of the luminous sign units with the letter forming face plate removed therefrom; Fig. 3 is an enlarged horizontal broken sectional view of the sign structure as substantially on the plane of line 3—3 of Fig. 1; Fig. 4 is a broken rear view of the sign structure; Fig. 5 is a face view of the board on which the sign units are mounted; Figs. 6 and 7 are plan and cross-sectional views respectively of a form of the 25 sign unit constructed for mounting in an ordinary lamp socket.

The sign shown in Figs. 1 to 5 consists of a back board or panel 8 carrying suitably spaced terminal sockets 9 and luminous interchangeable sign units in the form of blocks or slabs 10 having electrode terminals 11 on the backs of the same engageable in the sockets 9.

The blocks or slabs 10 are of glass, quartz or other suitable transparent, translucent or light 40 passing material and have formed in them a continuous convolute passage 12 extending substantially throughout the body of the block from one electrode to the other.

In the present disclosure each sign block is 45 made up of two molded or pressed glass front and back sections 13, 14 having matching portions of the convolute passage formed therein, these two sections being fused together at their meeting faces as indicated at 15 to form a unitary transparent block with a passage extending substantially throughout the entire area thereof between two different electrodes. This passage is filled 50 with neon, argon, or other luminescent medium, suitable electrodes such as indicated at 16 being provided at the ends of the passage and connected with the external terminals 11.

The terminal contacts are shown as arranged in diagonally opposite corners on the back of the slabs or plates and the sockets as correspondingly 60 placed on the back board, the sockets for two ad-

jacent characters being connected in series relation by suitable jumpers 17 and the end sockets of the board having external supply connections 18. This diagonal arrangement is desirable because of the bracing effect on the sign plates, the 65 plates then being supported at the top and bottom and for ordinary sizes being held supported solely by the current carrying sockets and terminals.

As the gas passage occupies practically the entire area of each sign plate and the discharge is through this continuous passage from one corner to the diagonally opposite corner, practically the entire area of the plate is made luminous. As shown in Fig. 3, the walls defining adjacent 70 branches of the convolute tube can be made quite thin and so maintain the passage unidirectional without appreciably or seriously cutting down the light emission. If desired to give a somewhat ribbed effect, these partition walls may be left 75 somewhat heavier. With the unit presenting when in use a substantially continuous or uniformly illuminated area, any or all portions of the surface may be covered or "masked" to form various 80 illuminated shapes or designs. In Figs. 1 and 2, 85 the substantially uniformly luminous units are shown as having face plates 19 applied as stencils thereover to form different letters, said plates being suitably secured, even by such simple means as gluing. In other variations of the invention, 90 the designs may be painted over the faces of the luminous panels and the invention contemplates any means by which desired luminous areas may be made visible while other areas are left masked.

To adapt the invention to ordinary electric light 95 sockets, a form of construction such as illustrated in Figs. 6 and 7 may be employed where the back section 14' of the luminous plate is shown as having a molded stem 20 carrying a screw shell contact 21 connected with one electrode 16a and an 100 end contact 22 connected with the other electrode 16b, said two electrodes being arranged in cavities 12a and 12b forming the terminals of the convolute passage 15', which in this case is of a 105 convolute generally circular form.

The last form of the invention presents a substantially circular luminous disc which may be left as a bright area of light or be masked to form various figures and designs as in the case first described. By the screw socket terminal form of 110 construction the interchanging of the units can be very quickly effected and standard sockets, with the proper external connections, may be employed.

The luminous sign panels may be made of such sizes and shapes, such as square or rectangular as shown in Figs. 1 and 4, that they will fit closely together and appear as a continuous sign board. The sign characters may be quickly interchanged to spell different words and the same luminous units may be quickly altered to form different let- 115 120

ters or characters, for instance, by painting different shapes or by substituting different stencil plates over the faces of the same. The latter feature enables a relatively small number of the luminous units to be used at different times to form an infinite variety of sign effects.

The previously molded front and back plates of the panels may be secured together in various ways, for instance, by fusion or by the use of a 10 suitable permanent transparent cement. The panel also may be made in a single piece with the tortuous passage molded or otherwise formed therein. The neck or necks at the back of the 15 panel in which the electrodes are located and which carry the outside terminals may be made as integral extensions, substantially as shown.

Where the luminous units are to be used for the letters of the alphabet, they may be made up in two sizes a narrow size to be used for letters 20 such as "T" and "J" and a double width size for the wide letters such as "M" and "W", etc., and in such a case the sockets 9 will be spaced to take the terminals of the narrow panels, alternate sets 25 of the sockets being used where the wider panels are placed. The back board 8 may be made of bakelite or other insulating material and the sockets which are mounted on this plate may be arranged in series or parallel relation. If in series 30 relation, special "jumpers" may be provided between successive sockets to carry the current, for instance across the spaces between different words 35 of a sign. These "jumpers" may simply be conductor wires carried by blank or "dummy" panels inserted between the "live" panels at the ends of different words. If stencils are employed as in 40 Fig. 2, these may be provided with clips or the like, so that they may be easily removed and quickly snapped into place. These clips, for instance, being in the form of spring fingers engaging over 45 the edges of the luminous panels. The internal electrode and external terminal may be made up as a single unit and be fastened in place by having the glass or other material molded about the same. The gas passage is of the proper cross-sectional area to give the desired illumination and is of a length with folds placed close enough together to provide the desired continuous luminosity of the panel.

What is claimed is:

50 1. An electric sign comprising a base-board, electric terminals on said base-board and luminous sign units interchangeably mounted on the board in engagement with selected terminals and each consisting of an internally illuminated body having a continuous convolute gas passage therein with the turns of the same in immediate juxtaposed relation to form a substantially uniformly luminous area when filled with luminous gas, a gas in said passage luminous under the discharge 55 of an electric current therethrough and electrodes for said gas located at the ends of said convolute passage.

60 2. A construction as in claim 1, with means for masking all but certain shaped areas of said luminous fields.

65 3. A construction as in claim 1, with removable means for variably masking all but certain predetermined shaped sections of said luminous fields.

70 4. A substantially continuously luminous electric sign unit comprising front and back plates having complementary portions of a continuous convolute gas passage arranged with the suc-

cessive turns of said passage in immediately adjoining relation to provide a substantially continuous uniformly luminous field when filled with luminous gas, said plates being secured together to complete said continuous convolute passage, 80 electrodes carried by the back plate at the ends of said passage, external contacts for said electrodes and a conducting gas in the continuous convolute passage.

5. In electric signs of the gas illuminated type, 85 transparent panels of interchangeable form and having electrodes with terminals on the backs of the panels and by which the panels may be mounted interchangeably on a suitable supporting base, each of said panels having a luminous gas passage therein of closely adjacent turns outlined at the face of the panel to form a desired design, said passage being in connection at its ends with the terminal electrodes, and an illuminating gas in said passage in communication with the electrodes, a base board having 90 sockets for the electrode terminals spaced and arranged in accordance with the spacing and arrangement of the electrode terminals on the panels.

6. In electric signs of the gas illuminated type, 95 transparent panels of interchangeable form and having electrodes with terminals on the backs of the panels and by which the panels may be mounted interchangeably on a suitable supporting base, each of said panels having a luminous gas passage therein of closely adjacent turns outlined at the face of the panel to form a desired design, said passage being in connection at its ends with the terminal electrodes, and an illuminating gas in said passage in communication with the electrodes, a base board having 100 sockets for the electrode terminals spaced and arranged in accordance with the spacing and arrangement of the electrode terminals on the panels.

105 6. In electric signs of the gas illuminated type,

transparent panels of interchangeable form and having electrodes with terminals on the backs of the panels and by which the panels may be mounted interchangeably on a suitable supporting base, each of said panels having a luminous gas passage therein of closely adjacent turns outlined at the face of the panel to form a desired design, said passage being in connection at its ends with the terminal electrodes, and an illuminating gas in said passage in communication with the electrodes, the electrode terminals on the panels being spaced diagonally of the panels and sockets provided for said terminals similarly spaced in diagonal relation.

115

7. In electric signs of the gas illuminated type, 120 transparent panels of interchangeable form and having electrodes with terminals on the backs of the panels and by which the panels may be mounted interchangeably on a suitable supporting base, each of said panels having a luminous gas passage therein of closely adjacent turns outlined at the face of the panel to form a desired design, said passage being in connection at its ends with the terminal electrodes, and an illuminating gas in said passage in communication with the electrodes, the electrode terminals on the panels being spaced diagonally of the panels, sockets provided for said terminals similarly spaced in diagonal relation and cer- 125

tain intermediate sockets of a series being directly connected independently of any panels.

8. A luminous electric panel, comprising complementary front and back plates secured together in face to face relation, one of said plates 130 having a continuous convolute depression in the face of the same with adjacent convolutions in immediately contiguous relation separated by thin walls to provide substantially uniform illumination throughout the field of said contiguous convolutions, the other plate engaging with said thin walls to form the complementary portions of said contiguous convolutions and one of said plates being transparent to light, a luminous medium in said convolute passage and electrodes 135 carried by the panel in electrical connection with the medium in the convolute passage.
